(57) **CLAIM**

We claim the ornamental design for an electrical linear drive decelerator, as shown and described.

DESCRIPTION

FIG. 1 is a front and right side perspective view of an electrical linear drive decelerator of the present invention; FIG. 2 is a bottom view thereof;

FIG. 3 is a top view thereof;

FIG. 4 is a rear view thereof;

FIG. 5 is a front view thereof; and,

FIG. 6 is a right side view thereof, the left side view being identical.
